UNITED STATES PATENT OFFICE.

ELMER O. EVANS, OF MEDIA, ILLINOIS, ASSIGNOR TO MORRIS S. EVANS AND JOHN W. WEVER, OF MEDIA, ILLINOIS, CHARLES W. LAYMAN, OF LOMAX, ILLINOIS, ADOLPH MUELLER, OF DALLAS, ILLINOIS, AND DANIEL ARTHAUD, OF WASHINGTON, IOWA.

CAR-COUPING.

SPECIFICATION forming part of Letters Patent No. 718,706, dated January 20, 1903.

Application filed May 2, 1902. Serial No. 105,640. (No model.)

To all whom it may concern:

Be it known that I, ELMER O. EVANS, a citizen of the United States, residing at Media, in the county of Henderson and State of Illinois, 5 have invented certain new and useful Improvements in Car-Couplers; and I do declare the following to be a full, clear, and exact description of the invention, such as will enable others skilled in the art to which it applies to make and use the same, reference being had to the accompanying drawings, and to the figures of reference marked thereon, which form a part of this specification.

My invention is a car-coupler, and relates to 15 that class of couplers known as the "Janney" type.

In the accompanying drawings, Figure 1 is a top plan view of my coupler. Fig. 2 is a longitudinal vertical sectional view of Fig. 1 20 on the line X X. Fig. 3 is a longitudinal horizontal sectional view, the top half of the coupler being removed to show the mechanism of the lower half. Fig. 4 is a cross-sectional view of the lower half of the coupler cut on 25 the line 4 4 of Fig. 3. Fig. 5 is a detail and perspective view of the lower and left-hand side of the jaw of the coupler. Fig. 6 is a bottom perspective view of the lock-plate. Fig. 7 is a perspective view of the knuckle, showing 30 the inner shoulder of the knuckle and the inner face of the locking-arm. Fig. 8 is an edge view of the trip-pin and the hood which covers the upper end of the same. Fig. 9 is a perspective view of the hood which covers 35 the upper end of the trip-pin, and Fig. 10 is a cross-sectional view of Fig. 9 on the line 10 10.

My invention is described as follows:

1 is a draw-head bifurcated at its front end and provided with side flanges 2, so that the 40 said draw-head may be made reasonably thin, yet strong, and in the upper face of said draw-head is a well or a depression 3, having around it a wall 4, and running back a considerable depth into said draw-head is a recess 5, and 45 running down through the upper wall of said recess or well is a square opening 6, and running down through the lower wall of the draw-head is a square opening 7, corresponding to

the opening 6. These openings 6 and 7 are for the purpose of receiving a trip-pin 8. The 50 upper part of said trip-pin is square and has running longitudinally through it for a part of its way a slot 9, and in this vertical slot is pivoted a trip-lever 10. This trip-lever consists of a single bar of metal having a shoulder 11 extending at right angles from its pivoted end, and in the free end of this trip-lever is a perforation 12. When this trip-pin 8 is down and in place, the front face of the shoulder 11 rests against the front wall 60 of the square opening 6. On said trip-pin and some little distance below the trip-lever is a shoulder 13, and this shoulder 13 rests under the front wall of the upper opening 6, so that when the said trip-pin is down its 65 shoulder 13 rests under and is kept from moving up by said wall, and when the free end of the trip-lever 10 is raised the right-angle shoulder 11 presses against the front wall of the opening 6, and this presses said trip-pin 70 back, and consequently the shoulder 13 out, from under the wall of the opening, releasing the trip-pin, so that it may be drawn up, and thus unlock the coupler. Said trip-pin 8 is provided with a lower enlargement 14, also 75 an under shoulder 15, and the extreme lower end 16 of this trip-pin is beveled rearwardly. On the inside of the left face of the lower half of the jaw 17 is a socket 18, (see Fig. 4,) and extending from the wall of said lower jaw and 80 one-half the way between the two walls of the said socket 18 is a lug 19. A lock-block 20, adapted to fit in the mouth of said draw-head and extending nearly across the same, is provided with a bifurcated knuckle 21, said 85 knuckle fitting in the said socket 18 and said lug fitting in the slot which bifurcates the said knuckle. The said lock-block is provided with a square opening 22, which is on an exact line with the square openings 6 and 7 and 90 through which the trip-pin 8 passes. Fig. 6 is a perspective view of said lock-block, in which an enlargement 23 shows the lower bulge of the knuckle 21, mentioned above, and in which the depressions 24 and 25 show the 95 tracks of a locking-arm 26 and its point 27, re-

spectively. Passing through said lock-block 20 is a horizontal perforation 28, (see Fig. 2,) and through the said trip-pin 8 passes a corresponding perforation 29, and between the 5 front wall of the square opening 7 and against the rear face of the trip-pin 8 is a spiral spring 30, and passing through the perforation 28, spring 30, and the perforation 29 is a bolt 31, and passing vertically through said bolt 31 is 10 a spring-pin 32. The forward end 33 of said bolt turns at a right angle to its body and fits in a depression 34 in the upper face of the lock-block 20, and extending forwardly from the depression 34 is another depression or 15 channel 35. This channel is to enable the mechanic to put the said bolt in position when the draw-head is all cast in one piece, which I prefer. The spring 30 holds the front face of the coupling-pin against the front walls of 20 the openings 6 and 7, and consequently holds the shoulder 13 under the front wall of the upper part of the coupler when the trip-pin is down, and when up holds the shoulder 15 on the lower wall of the coupler. The result 25 of this combination is that the said trip-pin may be moved rearwardly, and thus be raised; but it is never raised enough to allow its tapered end 16 to entirely escape from the lower opening 7, and the further result of this combination is that it only operates in conjunction 30 with the lock-block 20—that is to say, when the trip-pin is raised the locking end of said lock-block is also raised, and when the locking end of said lock-block is pressed down the pin 35 is also carried down with it. The upper end of said trip-pin is provided in each edge with a groove 36, and fitting over the top of said trip-pin is a hood 37, provided with internal tongues 38, which fit in the said grooves 36 40 and allow the hood to move up and down. The rear part of the said hood extends downwardly, forming a wedge 39 from its lower point 40 to its upper point 41. This hood is also provided at its upper end with a perforated elevation 42. Extending from said perforation 42 is a chain 43, and from the perforated end of the lever 10 is another chain 44, which is secured to chain 43 at a point a short 45 distance above the elevation of the hood. The chains are so constructed as to their 50 length that when pulled on the wedge is first moved up out of the way, and then the second operation is to draw up the end of the lever 10, which operation throws the trip-pin 55 rearwardly and releases its shoulder 15 from under the upper wall of the draw-head, and as the pin goes up, being secured to the lock-block 20, the free end of the lock-block 20 also goes up, and thus the coupler is unlocked and the spring 30. When the trip-pin 60 is carried up sufficiently high, the shoulder 15 is thrown forward and over the edge of the lower opening 7 and onto the upper face of the lower wall of the coupler.

65 The purpose of the wedge 37 is to keep the trip-pin tight up to the front and its shoulder 13 under the upper wall of the coupler,

so that there can possibly be no opportunity for the locking-arm, hereinafter described, to escape from behind the lock-block. As 70 the car moves and jolts and jostles along the tendency of the wedge is to constantly keep the trip-pin pressed to the front.

In the inner face of the left-hand jaw of the coupler is a recess 45, (see Fig. 3,) hereinafter described. The forward end of the right-hand wall 46 is bifurcated, and in this bifurcation is hinged a knuckle 47 by means of a pin 48, which passes through the perforations 49 in the forward end of said coupler 80 and through a corresponding perforation in said knuckle. Said knuckle is also provided with perforations 50, so that the said coupler may be coupled to other cars not provided with this coupler. Said knuckle is provided 85 with an outer or forward shoulder 51, which impinges against the point 52 of the forward end of said coupler. The object of this shoulder is to keep the knuckle from being thrown too far back, and thus the point 27 of the locking-arm 26 is prevented from coming with too 90 much force against the stop 53 in the front end of the coupler. (See Fig. 5.) This stop arrests the locking-arm at this point, and consequently the said arm is never allowed to 95 swing entirely out from the mouth of the coupler. It will be observed by reference to Fig. 3 that the point 27 of this arm extends outwardly a short distance and a little beyond the main arm and is curved or is made 100 with a swell which fits into the depressions 45, so that should the pin 48 by any means be broken or the knuckle or the hinge by any means become unhinged the said arm being held firmly between the face of the wall and 105 the face 54 of the locking-block (see Fig. 6) cannot be withdrawn, and consequently the coupler would not become uncoupled. Secured to the inner face and near the hinged part of said knuckle is the arm 26, above mentioned. Said arm has its rear part beveled nearly to an edge, so that it may pass under the lock-block 20, and the point of said arm is provided with a swell 27, as above described. The front face of said arm is nearly 110 vertical, but inclines a little rearwardly, while the locking-face 54 of the lock-block inclines a little under, so that the two inclines correspond. The purpose of these inclines is to allow the lock-block to be raised easily and 115 not impinge against the face of the locking-arm when being so raised. When the lock-block is raised, the said locking-arm escapes, the knuckle flies back, and the coupler is uncoupled. When the coupling-pin is raised 120 sufficiently, the shoulder 15 rests on the lower wall, and consequently holds the lock-block up, and thus, as above said, the arm 26 is permitted to escape until the point reaches 125 the stop 53.

The lower face of the lock-block has two tapering recesses 24 and 25, respectively, so that when the locking end of said lock-block is down the locking-arm 26 and its point 55

may pass under said tapering recesses and pass beyond the locking edge 54 of said block, and as this is done the point 55 strikes against the enlargement 14 of the trip-pin and throws the shoulder 15 back off of the wall, and the weight of the pin and the lock-block causes the pin to immediately drop and the spring 30 presses it forward and the shoulder 13 immediately passes under the other wall of the 10 coupler and the wedge 39 slips down behind the pin and keeps it tight in place.

My full-sized coupler is intended for freight and passenger steam-cars and heavy cars of all kinds; but the coupler may be smaller 15 and lighter and adapted to street-cars and light coaches.

Having described my invention, what I claim as new, and desire to secure by Letters Patent, is—

1. An automatic car-coupler, consisting of a draw-head, having in the inner side of one of its walls, a recess, the same wall being bifurcated at its front end; a socket in the other side wall, and a lug extending across the said 20 socket; a knuckle hinged in said bifurcation, having an outward shoulder, adapted to impinge against the end of the wall, to which it is hinged; an arm integral with, and extending from the rear face of said knuckle, and 25 having its rear side beveled down nearly to an edge; a point extending rearwardly from the free end of said arm, and terminating in a swell, adapted to fit in said recess; the rear edge of said arm adapted to lie close against 30 the face of said wall, and its point to impinge against a stop in the mouth of the draw-head; a lock-block provided with a square vertical perforation, and having in its lower face two inclined recesses; said lock-block adapted to 35 straddle the said lug and to fit in the socket, just described; a stop secured to the lower wall, and adapted to arrest the point of the locking-arm, the upper and lower walls provided with square vertical openings, on a line 40 with the opening of the lock-block; a trip-pin provided with a vertical slot, on each side vertical grooves, an enlargement, forming upper and lower shoulders, and a perforation through its center; said trip-pin passing 45 through the square openings, above mentioned, its upper shoulder adapted to rest under the upper wall, and its lower shoulder on the lower wall of the coupler; a bolt passing 50 through said lock-block, and trip-pin, its front end bent at an angle, and resting in a right-angle depression in the upper face of the lock-block; a spring-pin passing vertically through the lock-block, and said bolt; a spiral spring resting against the rear wall of 55 60 the opening in the lock-block, and the rear face of the trip-pin; a hood provided with internal tongues, and terminating in a wedge; said hood adapted to work up and down on the upper end of said trip-pin, and the wedge 65 between the rear face of said trip-pin, and the wall of the opening; a lever, having a shoulder, and hinged in the slot of said trip-

pin, and adapted, when its free end is raised, to throw the said pin back, and release its shoulder from under the upper wall of the 70 draw-head; chains, one secured to the hood, and the other to the free end of the trip-lever, and so attached when the chains are pulled on, the wedge will be raised first, and then the lever next, and then the trip-pin raised, 75 thus raising the lock-block, and uncoupling the car, substantially as shown and described and for the purposes set forth.

2. An automatic car-coupler, consisting of a draw-head, having in the inner side of one 80 of its walls a recess, the same wall being bifurcated at its front end, and a socket in the other side wall, and square vertical openings in its upper and lower walls; a knuckle hinged in said bifurcation, having an outward shoulder, adapted to impinge against the end of the wall to which it is hinged; an arm extending from the rear face of said knuckle; a point extending rearwardly from the free end of said arm, and terminating in a swell, adapted 85 to fit in said recess; a lock-block, provided with a square vertical perforation, and having a knuckle 21 adapted to fit in said socket; a stop secured to the lower wall, and adapted to arrest the point in the locking-arm; a trip- 90 pin, having an enlargement, forming an upper and lower shoulder, and a perforation passing through the square openings just mentioned, its upper shoulder adapted to rest under the upper wall, and its lower shoulder on the lower wall of the draw-head; a bolt securing 95 said trip-pin in the lock-block; a spiral spring resting against the rear wall of the opening in the lock-block, and the rear face 100 of the trip-pin; a hood, fitting over the top of the trip-pin, and having one side terminating in a wedge, working between the rear wall of the upper opening, and the rear face of the trip-pin; a lever hinged to said trip- 105 pin, and adapted, when its free end is raised, to throw said pin back, and release its shoulder from under the upper wall of the draw- 110 head; chains, secured to said hood, and the free end of said trip-lever, and adapted to 115 pull first on the free end of the lever, and then on the upper end of the hood, substantially as shown and described and for the purposes set forth.

3. An automatic car-coupler, consisting of a draw-head, one wall being bifurcated at its front end, and having in the other wall, a knuckle-socket; square vertical perforations through its lower and upper walls; a knuckle hinged in said bifurcation; an arm extending 125 from the rear face of said knuckle; a point extending rearwardly from the free end of said arm; a lock-block provided with a square vertical perforation, having a knuckle 21 adapted to fit in said knuckle-socket; a stop 130 secured to the lower wall, and front end of said draw-head, and adapted to arrest the point of the locking-arm; a trip-pin, having an enlargement, forming an upper and lower

shoulder, and a perforation passing through its center, said trip-pin passing through the said perforations of the draw-head above mentioned; a bolt passing through said lock-block, and trip-pin; a spiral spring resting against the rear wall of the opening, in the lock-block, and the rear face of the trip-pin; a hood, fitting over the top of said trip-pin, and having one side terminating in a wedge; 5 said hood adapted to work up and down on the upper end of said trip-pin, and a wedge between the rear face of said trip-pin, and the wall in the opening; a lever pivoted to said trip-pin, and adapted, when its free end is

raised, to throw the trip-pin back; chains, 15 one secured to the hood, and the other to the arm of said lever, and so attached that when the chains are pulled on, the wedge will be raised first, the lever next, and then the trip-pin, substantially as shown and described and 20 for the purposes set forth.

In testimony whereof I affix my signature in presence of two witnesses.
